UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

STAY-BOLT-TESTING DEVICE.

1,236,066.

Specification of Letters Patent.

Patented Aug. 7, 1917.

Application filed July 25, 1916. Serial No. 111,309.

To all whom it may concern:

Be it known that I, ETHAN I. DODDS, a citizen of the United States, and a resident of Pittsburgh, in the county of Allegheny and State of Pennsylvania, have invented certain new and useful Improvements in Stay-Bolt-Testing Devices; and I do hereby declare the following to be a full, clear, and exact description of the invention, such 5 as will enable others skilled in the art to which it appertains to make and use the same.

This invention relates to improvements in means for testing stay bolts of boilers,— 15 one object of the invention being to provide simple and efficient electromagnetic means which will operate promptly to detect a broken bolt.

A further object is to so construct a magnetic bolt testing device that it may be 20 readily handled and manipulated and which shall be positive and certain in action.

With these and other objects in view the invention consists in certain novel features 25 of construction and combinations of parts as hereinafter set forth and pointed out in the claims.

In the accompanying drawings; Figure 1 is a view in elevation of a bolt tester showing 30 an application of my improvements; Fig. 2 is a vertical sectional view, and Fig. 3 is a plan view.

In the application of stay bolts to boilers, it is customary to attach one end of the bolt 35 1 to the inner boiler sheet 2 and to provide the other end of the bolt with a spherical or partly spherical head 3 having a bearing in a sleeve 4 passing through the outer sheet 5 of the structure. This sleeve is externally 40 threaded to facilitate its attachment to the sheet 5 and also to receive a cap 6 which encloses the head of the bolt; the structure of the assembled parts being such as to leave a clearance 7 between the head of the bolt 45 and the inner face of the cap. Should the bolt break at any point, the head thereof will become loose within the cap 6 and may move therein through the clearance space 7 and engage the inner face of said cap.

50 My improved detector is designed to cause the head of a broken stay bolt to forcibly engage the cap and by the sound or vibration produced by the striking of the bolt head against the cap, denote the fact that 55 the bolt is broken. Should no sound or

vibration occur when the detector is applied, this fact will denote the integrity of the bolt.

The improved testing device or detector comprises a magnet frame or shell 8, the head 9 of which is formed with a central enlargement 10 which forms a seat for the upper end of a laminated core 11 secured in place as hereinafter explained. The lower end of the magnet frame or shell is closed 60 by a non-magnetic plate 12 and the latter is made with a central opening 13 through which the free end of the magnet core 11 passes. For convenience of manufacture, the laminated core 11 may be made angular 65 in cross section and its free projecting end is made with a recess 14 to engage over and conform to the contour of the cap 6 of the stay bolt structure.

A hollow handle 15, which may be made 70 of aluminum, is mounted upon the head 9 of the magnet shell and the base 16 of said handle may be formed with a flange 17 to rest on said head so as to provide a ventilating space 18. The base 16 of the handle 75 may be secured to the head 9 by means of screws 19 and also by means of a large central screw 20, the latter passing freely through a hole 21 in the head of the magnet frame and entering the upper end of the 80 magnet core 11 so as to secure the latter firmly to its seat. On leg, 22, of the handle 85 may be made solid and integral with the base plate 16, while the other leg 23 is made tubular and may also be integral with the 90 base plate. Thus the entire handle structure may be made or cast in a single piece.

The coil 24 of the magnet occupies the angular space within the frame or shell 8 and around the core 11, and the terminals of 95 this coil pass through a hole 25 in the head 9 of the magnet frame and enter the tubular handle. One end of the handle is open for the passage of the leading-in wires of the magnet coil and the bore of the tubular handle is preferably contracted somewhat at its open end as indicated at 26 for the reception of a flexible coil 27 which serves to protect the leading-in wires 28,—said flexible coil being secured in place by means of a screw 100 29 or a plurality of such screws.

A suitable switch 30 will be suitably placed in the circuit of the magnet coil, and may be located on the handle portion of the structure.

When the recessed end of the magnet core is applied to a cap 6 of the stay bolt structure, the closing of the circuit of the magnet coil will result in the generation of magnetic lines of force which will pass through the iron cap and head of the stay bolt, thus causing the forcible engagement of the head of the bolt with the inner face of the cap, in the event that the bolt is broken. Such forcible engagement of the bolt head with the cap will cause a sharp sound or jar which will indicate to the operator that the bolt is broken,—viz., that the parts thereof have become severed.

Should the bolt break in proximity to the inner sheet, 2, it would be liable to drop to an inclined position and the head might bind in its bearing in the sleeve 4 due possibly to a collection of incrustation which might enter by reason of the loosened bearing of the head of the broken bolt. Under such conditions, a magnet structure such as above described may be applied to the inner head of the broken bolt so as to cause the body of the depending broken bolt to be raised or moved sufficiently to insure the operation of the magnet structure applied to the cap to cause the head of the bolt to strike the cap as previously explained.

Having fully described my invention what I claim as new and desire to secure by Letters-Patent, is:—

1. A testing device for stay bolts in boiler

structures, comprising a shell having a head at one end, a non-magnetic plate secured to the other end of said shell and having a hole therein, a core secured to the head of the shell and passing through the hole in said non-magnetic plate, the free end of said core having a recess to conform approximately to the contour of the cap of a staybolt structure, a coil within said shell encircling the core, and a handle secured to the head of said shell.

2. A testing device for staybolts in boiler structures, comprising a shell having a head at one end provided with a central hole, a plate secured to the other end of said shell and having a central hole, a core extending through the shell and through the hole in said plate and recessed at its free end, a coil encircling said core within the shell, a handle having a base mounted on the head of the shell, a screw passing through said base and through the central hole in the head of the shell and entering said core, and circuit controlling means for the coil adjacent to said handle.

In testimony whereof, I have signed this specification in the presence of two subscribing witnesses.

ETHAN I. DODDS.
